TURRET PRESS

Oscar W. Johnson, Rochester, N. Y., assignor to
 The American Laundry Machinery Company,
 Cincinnati, Ohio, a corporation of Ohio

Application July 24, 1931, Serial No. 552,886
 Renewed February 17, 1934

15 Claims. (Cl. 68—9)

My invention relates to bosom presses and, particularly, to bosom presses of the turret type in which a rotating frame or turret has a work receiving bed or buck provided on both of its diametrically opposite disposed ends remote from its pivotal point and arranged to be presented alternately below a fixed head and then moved upwardly under sufficient pressure against the head to complete the pressing operation.

10 The objects of my invention are to provide a machine in which the several operations, namely, rotation of the frame or turret, movement of the pressing beds or bucks into and out of engagement with the pressing head, and causing a suction if air from within the hollow pressing beds or bucks whose upper work receiving surface is perforated or padded, work automatically after being operator initiated by a single operator-operated means and wherein none of the operations except the performance of proper lays of material on the pressing beds or bucks and operation of the single operator-operated means are required to be done manually; and to provide an efficient and yet a relatively simple machine such that production will be speeded up and good pressing results will be produced.

15 Various other objects and advantageous features of my invention will be seen in the following description and one embodiment thereof may be seen in the accompanying drawings wherein similar characters of references designate corresponding parts, and wherein:

Fig. 1 is a front elevation showing a machine constructed in accordance with my invention; Fig. 2 is a rear elevation of the machine shown in Fig. 1; Fig. 3 is a detail end view taken on the line 3—3 of Fig. 2 showing the frame or turret stop mechanism in normal position; Fig. 4 is a view similar to Fig. 3 but showing the frame or turret stop mechanism in a released or operated position; Fig. 5 is a sectional view taken on the line 5—5 of Fig. 4; Fig. 6 is a sectional view taken on the line 6—6 of Fig. 2 showing the turret operating mechanism in unoperated position; Fig. 7 is a view similar to Fig. 6 showing the frame or turret operating mechanism in operated position; Fig. 8 is a sectional view showing the inlet and exhaust valves for the power cylinder, and Fig. 9 is a view similar to Figs. 3 and 4 but showing both operator-operated treadles in up position.

Referring to the drawings, I have shown a pressing machine consisting of a suitable base 1 provided with two spaced upright posts, 2 at one end thereof and a single post 3 at the opposite end thereof. Midway between the end posts 2

and post 3, the base 1 is provided with a cylinder 4 having a vertically traveling piston 5 therein whose rod 6 protrudes through the upper end wall of the cylinder. A frame 7 is pivotally mounted on the post 3 in such manner that either one of its duplicate ends can be moved to register with the piston rod 6 and since both ends of the frame 7 are identical, only one end of the frame need be described.

Each end of the frame 7 is provided with a vertical bore 8 in which a shaft 9 is fitted to slide vertically, the shaft 9 carrying a pressing bed or buck 10 on its uppermost end that is adapted to cooperate with a stationary pressing head 11 rigidly secured to the under side of a beam 12 mounted on the upper ends of the posts 2 and 3. A metal tray 13 is also carried by the shaft 9 and is disposed below the pressing bed or buck 10. In the normal position of the various parts of the apparatus, the lowermost end of the shaft 9 just clears the upper end of the piston rod 6.

Each end of the frame 7 is also provided with a rigid depending tapering pin 14 and a lateral extension 15 provided with a vertical bore in which a pipe 16 is rigidly secured and adapted to receive a smaller pipe 17 that leads from the interior of the pressing bed or buck 10 and slides within the pipe 16 as the pressing bed or buck 10 is moved upwardly and downwardly. Two small drain pipes 18 connect the lower portions of the hollow pressing bed or buck with the pipe 17 whereby the condensed vapor within the buck may be drained off. A stuffing box 19 is provided at the upper end of the pipe 16 to form an air tight joint so that suction in the pipe will cause a suction on the interior of the pressing bed or buck. The lowermost end of the pipe 16 is connected by way of a pipe 20 to the central portion of the frame 7 where the frame is provided with an annular hollow space 21 surrounding the post 3 and opening downwardly into another similar annular hollow space 22 formed in the base 1 and also surrounding the post 3. A suitable pipe 23 (Fig. 2) connects the hollow space 22 with the suction end of a fan 24 driven by a motor 25, the fan and motor being mounted on a suitable bracket secured to the base 1. Thus, a means for creating suction within the pressing beds or bucks is provided.

As a means for locking the frame carrying the pressing beds or bucks against movement about the pivot 3 when one of the pressing beds or bucks is in registry with a stationary pressing head 11, each of the shafts 9 which carry the pressing beds or bucks 10 is substantially of the

same diameter as a piston rod 6 whereby when the piston rod is moved upwardly by air pressure being admitted below the piston 5, it will enter the bore 8 in the frame whereby the frame 7 will be locked against rotation. However, as the upper end of the piston rod 6 moves downwardly sufficiently to be below the frame 7, the frame is free to be turned about the post 3 as a pivot so far as this particular locking means is concerned. It will be understood that the pressing beds or bucks 10 are moved upwardly and pressed tightly against the stationary head 11 alternately when compressed air is admitted below the piston 5 and when air is released or permitted to exhaust into the atmosphere, the pressing beds or bucks 10 and the piston 5 will move downwardly to their normal positions by force of gravity.

In accordance with my invention, I provide an automatic operating mechanism for rotating the frame 7 about the post 3 one-half revolution or 180° at a time as soon as the piston 5 reaches its lowermost unoperated position to release the lock on the frame. Such automatic operating mechanism consists of a bell crank lever 26, as shown in Figs. 1, 2, 6 and 7, loosely mounted on a shaft 27 that has its ends secured in suitable lugs 28 secured rigidly to the top of the base 1. One arm of this bell crank lever 26 is arranged to swing in the path of a pin 29 mounted on the extension 15 of the frame 7 and extending radially outwardly therefrom. The other arm of the bell crank lever has a bifurcated end with a pair of aligned pins 30 extending from the opposed surfaces of such ends, there being sufficient space between the free ends of the pins 30 to straddle a vertically extending rod 31 rigidly secured to the piston 5 and extending upwardly through a perforation provided therefor in the upper end of the air cylinder 4. A block 32 provided with a perforation is arranged to slide freely on the rod 31 and is moved upwardly with the rod by means of a transversely extending pin 33 carried by the rod and downwardly by a transversely extending pin 34 also carried by the rod 31.

The positions of the rod 31 and the shaft 27 relative to the bell crank lever 26 are such that the pins 30 will always be in contact with the block 32, the action of the bell crank lever 26 being controlled by the position of the block 32. That is, when the block 32 is in its up position, as shown in Fig. 6, the pins 30 will be in their up position, and when the block 32 is in its down position, as shown in Fig. 7, the pins 30 will be in their down position towards which position they are at all times urged by a coiled spring 35, as shown in Fig. 2, which has one end secured to the bell crank lever 26 and the other end secured to a tensioning disk 36 loosely mounted on the shaft 27. Such coiled spring preferably extends about the shaft 27 and is placed under the desired tension by turning the disk 36 counter-clockwise and securing it in its desired position by turning a screw 37 threaded into the lug 28 to have its end extend into one of a plurality of notches 38 provided in the periphery of the disk 36. Thus, the bell crank lever 26 may be constantly spring pressed to move counter-clockwise about the shaft 27 but may be prevented from doing so by the pins 30 coming into contact with the block 32. The tension of the spring 35 is adjusted to such a degree that the tension will be sufficient to move the frame one-half revolution or 180° when the

bell crank 26 is released, this spring force being resisted by the block 32 on the rod 31. Therefore, to guard against bending of the rod 31 against which lateral force is expended, a suitable bracket 39 is rigidly mounted on the top of the cylinder 4 and provided with a vertical guideway 40 in which the block 32 is arranged to slide.

In operation, when one of the pressing beds or bucks is being moved upwardly into pressing engagement with the fixed pressing head 11, the other pressing bed or buck is in a position away from the head 11, as shown in Figs. 1 and 2, and the only time that there is no pressing bed or buck in pressing engagement with the fixed head 11 is while one pressing bed or buck is moving downwardly away from the head 11, while the frame 7 makes a one-half revolution, and while the pressing bed or buck next brought into registry with the head 11 is moving upwardly into pressing engagement therewith. When a pressing bed or buck has been moved upwardly against the fixed head 11, the operating parts are in the position shown in Fig. 6, and when the frame 7 has completed its next one-half revolution, the parts are in the position shown in Fig. 7. However, in actual operation, the parts never come to a complete stop in the position shown in Fig. 7 but are left in such position at the close of a day's run by means of a shut-off lever and suitable apparatus hereinafter described.

The next action of the apparatus in operation and after the parts are in the position shown in Fig. 7, is upward movement of the piston 5 under the influence of fluid pressure which will move the block 32 until the parts are in the positions shown in Fig. 6. One arm of the bell crank lever 26, in moving from the position shown in Fig. 7 clockwise to the position shown in Fig. 6 wherein it engages the pin 29, passes the pin 29 on the frame 7 and to permit such passing the pin 29 is mounted on the free end of an arm 41 which is pivotally mounted as at 42 on the frame 7 so that the pin 29 can swing upwardly in an arcuate path about the pivot 42, the arm 41 carrying the pin 29 normally retaining its proper position against a stop 43 as shown in Fig. 7 by gravity. With this construction, it will be apparent that the one arm of the bell crank lever 26 will, in one of its positions, take against the pin 29 and push the frame 7 with sufficient force to cause it to make a one-half revolution each time the block 32 is moved downwardly by final downward movement of the piston 5, movement of the frame being accomplished by action of the spring 35.

Each time the frame 7 is moved by the spring pressed bell crank lever 26 for one-half revolution as hereinbefore described, the frame 7 is stopped at exactly the end of a one-half revolution by mechanism provided at that end of the frame 7 remote from the head 11. This stop means comprises an upwardly sliding spring pressed locking block 44 (Figs. 3, 4 and 5) provided with a tapering hole or opening 45 in the center of its upper surface with which the tapered pins 14 on the frame 7 cooperate to provide a lock. The block 44 is arranged to slide freely vertically in a bracket 46 which is rigidly secured to an extension on the base 1 and the block is normally held in its uppermost position by a coiled expanding spring 47 interposed between the under side of the block and a lug 48 integral with the bracket 46. In the construction shown, the frame 7 with the depending tapering pins 14 thereon rotates clockwise when viewed from above and the

top of the block 44 is inclined downwardly from its center toward one side so that as a pin 14 contacts with the inclined surface of the block, the block will be cammed downwardly against the upward pressure of the spring 47 and, as the pin passes backwardly from the center of the block, the block will slide on a rearwardly extending inclined surface to permit the block to be lifted by the spring 47 gradually. Thus, as the frame 7 approaches the end of its one-half revolution, one of the pins 14 depresses the block 44 and enters the tapering hole or opening 45 thereby stopping further rotation of the frame 7 in either direction. Thus, another locking means is provided to be effective prior to movement of the piston rod 6 into the bore 8.

To release the frame 7 for further rotation and operation of the machine, the block 44 must be moved downwardly against the resistance of the spring 47 and, to this end, a means is provided consisting of a treadle 49 (Figs. 1, 2 and 4) pivoted at 50 to a rearwardly extending lug 51 integral with the bracket 46. The treadle 49 carries a laterally extending pin 52 on which a bar 53 is pivotally mounted substantially at its center, the free ends of the bar being connected to the block 44 by means of links 54 extending upwardly on either side of the spring 47. With this construction, when the free end of the treadle 49 is depressed, the block 44 is moved downwardly against the tension of the spring 47. The bar 53 or a set screw 55 attached thereto is arranged to contact with the under side of the lug 48 to limit the upward movement of the block 44, the set screw being provided so that the limit of movement of the block 44 can be adjusted as desired.

Operative connections are provided between the treadle 49 and an exhaust valve in such manner that when the treadle is depressed the exhaust valve is opened and the piston 5 with the buck 10 which is under the head 11 will move downwardly, the frame 7 not rotating until the piston 5 is practically in its lowermost position as above described.

In order to relieve the operator of the necessity of holding the treadle 49 in the down position until the piston 5 reaches its lowermost position and the frame 7 starts to move, means are provided for automatically locking the treadle in its lowest depressed position which consists of a spring pressed latch 56 pivotally mounted on the block 44 as at 57 in such manner that its free upper end can swing into or out of the path of depending lugs 58 integral with the frame 7 and which are conveniently formed on the bosses 59 to which the pins 14 are secured or of which the pins form a part. The latch 56 is so pivoted that its upper end will swing in a plane parallel to the plane of the post 3 and, as the frame 7 approaches the end of its one-half revolution, the upper end of the latch 56 is cammed out by the lug 58 in a direction away from the post 3 and against the tension of a spring 60 (see Fig. 5). Reversely, when the block 44 is moved downwardly by depressing the treadle 49, the upper end of the latch 56 is moved by spring 60 in a direction toward the post 3 and under the lug 58 to retain the block 44 in a depressed position (Figs. 4 and 5). Fig. 4 shows the parts in the positions they assume when the treadle 49 is being held in a depressed position and Fig. 5 shows the parts in the positions which they assume when the treadle 49 is released but before the frame 7 has started its one-half revolution movement, that is, with the upper end of the

latch 56 engaging the lug 58 and thus preventing upward movement of the block 44.

A treadle 61 is provided which, when depressed, opens valves and passages to permit compressed air to pass into the cylinder 4 for lifting the piston 5 and causing pressing engagement between one of the pressing beds or bucks 10 and fixed pressing head 11 and the treadles 49 and 61 are so interlocked that both treadles cannot be depressed at the same time but are free to be in a raised position simultaneously. This interlocking mechanism comprises a bell crank lever 62 pivotally mounted as at 63 a short distance rearwardly of a horizontal pin 64 on which the treadle 61 is pivotally mounted. The short arm of the bell crank lever 62 extends toward the pin 64 and is provided with a laterally extending pin 65 about midway between the pivotal mounting 63 and pin 64, the laterally extending pin 65 being disposed in a slot provided in a rearward extension 66 of the treadle 61. The long arm of the bell crank lever 62 is provided with a laterally extending lug 67 which lies below and in the path of the treadle 49 in such manner that the long arm will be moved downwardly about the pivot 63 when the treadle 49 is depressed. It follows that the treadle 49 will be lifted by such connection when the treadle 61 is depressed and the free ends of bell crank lever 62 are raised, while the treadle 61, if in depressed position, will be raised when treadle 49 is depressed. Another rearward extension 68 on the treadle 61 has the lower end of a vertically moving rod 70 pivotally connected to its free end as at 69, the upper end of the rod 70 being guided by and sliding freely through a perforation provided in a lug 71 (Figs. 1 and 2) that is secured on the base 1 and whose upper extremity is located in the circular path of two diametrically opposed perforations provided in an annular horizontal flange 72 integral with the frame 7. The length of the rod 70 with respect to the distance between the treadle 61 and flange 72 is such that the treadle 61 can only be depressed when the upper extremity of the rod 70 registers with one of the two perforations in the flange 72. That is, the upper extremity of the rod 70 normally contacts with the lower surface of the flange 72 to prevent the rod from being moved upwardly and the treadle 61 from being depressed, the location 50 of the perforations being such that when the rod 70 registers with one of the perforations in the flange 72 the one buck 10 registers with the head 11 and one of the tapered pins 14 is locked in the block 44 so that the apparatus is in a position to have one of the beds or bucks 10 forced upwardly into contact with the head 11 by admitting fluid pressure into the cylinder 4 below the piston 5.

Fluid pressure, in this instance, compressed air, from a source of supply is conveyed to the apparatus through the pipe 73 which is connected to the intake 74 of a suitable valve mechanism as shown in Figs. 1 and 8. As shown, the intake valve 75 is open and an exhaust valve 76 is closed so that compressed air is free to pass from the intake 74 through a port 77 into the cylinder 4 below the piston 5. It follows, when the positions of the valves 75 and 76 are reversed, compressed air is prevented from passing to the cylinder 4 and the fluid pressure from below the piston 5 is free to pass out of the cylinder through the port 77, past the valve 76, and out to the atmosphere through an exhaust pipe 78. As shown in Fig. 1, a pipe 79 is connected between 75

the cylinder 4 above the piston 5 and the exhaust 78 to permit the air above the piston 5 to escape during the time the piston is being forced upwardly by compressed air in the working stroke 5 and to permit air to enter the cylinder above the piston when the piston moves downwardly by gravity, in which instance, the exhaust valve 76 is open.

The valves 75 and 76 are arranged to be operated in unison and oppositely. That is, when one valve is open the other is closed and vice versa. Such action is conveniently accomplished by connecting the valve stems of the valves by suitable links 80 to the opposite ends of a walking beam 81 pivoted at 82 to a bracket on the base 1. One end of the walking beam 81 is extended outwardly beyond one of the link connections where it is provided with a vertical perforation through which a rod 83 is adapted to slide, the lower end of the rod 83 being pivotally connected as at 84 to one end of a walking beam 85 pivotally mounted as at 86 to a bracket on the base 1. The other end of the walking beam 85 is operatively connected by a link 87 to a boss 88 integral with the treadle 61 and extending laterally therefrom in front of the treadle pivot pin 64 in such manner that the one end of the walking beam will always move upwardly and downwardly with the treadle 61 and the opposite end 30 of the beam will always assume opposite positions. Adjusting nuts 89 are provided above and below the walking beam 81 on the rod 83 and suitable coiled expanding springs 90 are interposed between the nuts 89 and the walking beam 81 whereby the up and down movement of the walking beam 85 transmitted to the walking beam 81 will be through the springs 90.

With the above construction, the inlet valve 75 for compressed air will be open when the treadle 61 is down (Figs. 1, 2, 3, and 8) and to have the treadle 61 automatically depressed whenever the frame 7 is turned to a position to have one of the two perforations in the flanges 72 register with the top end of the rod 70 so that the piston 5 will be automatically moved upwardly and one pressing bed into engagement with the fixed pressing head, a coiled contracting spring 91 is provided to yieldingly move one end of the walking beam 85 upwardly whereby the treadle 61 will be moved downwardly. Such spring 91 is conveniently connected between the end of the walking beam 85 adjacent the rod 83 and a bracket 92 secured to the base 1, the bracket being adapted to be lowered so that the spring 91 can be disconnected when it is desired to dispense with the automatic feature, for instance, at the close of a day's work. However, the same result can be accomplished by lowering the spring fastening on the bracket and to conveniently lower the spring fastening for such purpose, the upper end of the spring 91 is shown attached to the lower end of a vertically sliding rod 93 which, by means of its bent upper end that may take the form of a handle 94, can be secured in an up position to be supported on the top of the tubular portion of the bracket 92 or in a lower position to have its bent end rest in the lower part of a slot provided in the tubular portion of the bracket 92.

In operation of the apparatus, to start the operation of the machine, the handle 94 is set in its up position as just described which will cause operation of the piston 5 to press the aligned pressing bed or buck 10 against the head 11. During this time the lay of the goods is made on the

left-hand buck as seen in Fig. 1 and then the left-hand treadle or off-treadle is depressed by the operator which will cause the one pressing bed or buck to fall away from the head, the frame 7 to be turned a one-half revolution, and compressed air to be admitted to the lower end of the cylinder 4 to press that particular aligned buck up against the head. At this time, the other buck is in accessible position to receive another lay of goods. Thus, the only act necessary on the part of the operator is to make the proper lay of goods and depress the left-hand treadle which is the treadle 49. Also, as hereinbefore stated, at the close of a day's work the handle 94 may be set in its low position to have the pressing bed or buck in alignment with the head dropped to its unoperated position.

Referring to the drawings and the preceding description, it will be seen that I have provided a device embodying numerous novel and advantageous features. For instance, I have provided a device in which the several operations, namely, rotation of the frame or turret and movement of the pressing beds or bucks into and out of engagement with the pressing head, work automatic 25 after being operator initiated by a single operator-operated means and wherein none of the operations except the performance of proper lays of material on the pressing beds or bucks and operation of the single operator-operated means 30 are required to be done manually. Means are also provided for causing a suction of air from within the hollow pressing beds or bucks whose upper work receiving surfaces are perforated or padded. I have also provided a mechanism such 35 that both of the pressing beds or bucks may be brought to a lowered position at the end of a given length of pressing operation, for instance, a day's run, instead of leaving one of the pressing beds or bucks in engagement with the fixed 40 pressing head. In my device, the same operator-operated means may control only the operation of the locking means or may control both the locking means and the actuation of the entire 45 pressing mechanism as in initially starting the apparatus in operation at the beginning of a day's run. Various other advantageous features will be readily apparent.

What I claim is:

1. Apparatus of the class described, comprising an ironing member, a movable frame provided with a plurality of work supporting members adapted to be carried by frame movement into and out of registry with said ironing member, means for producing relative approach and separating movement between said ironing member and a work supporting member in registry therewith, means controlled by relative separating movement of said work supporting and ironing members for moving said frame to register another work supporting member with said ironing member, and means controlled by frame movement and upon movement of a work supporting member into registry with said ironing member and effective upon said first named means to cause the same to produce relative approach movement between said members.

2. Apparatus of the class described, comprising an ironing member, a rotatable frame provided with a plurality of work supporting members adapted to be carried by frame movement into and out of registry with said ironing member, means for producing relative approach and separating movement between said ironing member and a work supporting member in registry

therewith, means controlled by relative separating movement of said work supporting and ironing members for rotating said frame to register another work supporting member with said ironing member, means controlled by frame rotation and upon movement of a work supporting member into registry with said ironing member and effective upon said first named means to cause the same to produce relative approach movement between said members, and means for preventing operation of said last named means until such registration takes place.

3. Apparatus of the class described, comprising a fixed pressing head, a movable frame provided with a plurality of pressing beds adapted to be carried by frame movement into and out of registry with said fixed head, means for producing relative approach and separating movement between said fixed head and a bed in registry therewith, means controlled by relative separating movement of said head and bed for moving said frame to register another bed with said head, a controller for said approach and separating movement-producing means, and a yielding means normally tending to move said controller to a position wherein it will be effective on said movement-producing means to cause its operation, said movable frame being provided with means effective upon said controller and arranged to prevent such operation thereof except when said head and a bed member are in registration.

4. Apparatus of the class described, comprising an ironing member, a frame provided with a plurality of work supporting members and movable to carry said work supporting members into and out of registry with said ironing member, means for producing relative ironing approach of said work supporting and ironing members when in registry, a controller for said means, and a yielding means normally tending to move said controller to a position wherein it will be effective on said first named means to cause its operation, said movable frame being provided with means effective upon said controller and arranged to prevent such operation thereof except when said members are in registration.

5. Apparatus of the class described, comprising a head member and a plurality of bed members, a rotatable support for said bed members movable to bring said bed members into and out of registry with said head member, means for producing relative ironing engagement between the head and the bed in registry therewith, actuating means including a trigger mechanism cocked by movement of a bed into ironing engagement with the head and released by movement of a bed out of ironing engagement with the head for moving said bed support to register another bed with the head, and means whereby operation of said ironing engagement producing means is controlled by movement of said bed support in bringing a bed into registry with the head.

6. Apparatus of the class described, comprising a head member and a plurality of bed members, a rotatable support for said bed members movable to bring said bed members into and out of registry with said head member, cylinder and piston means for producing relative ironing movement between the head and the bed in registry therewith, power storage means having operative connections for rotating said support, said cylinder and piston means having an operative connection for storing power in said storage

means, and means for restraining said stored power and for later utilizing the same for rotating said support.

7. Apparatus of the class described, comprising a head member, a rotatable frame provided with a plurality of bed members adapted to be carried by frame rotation into and out of registry with said head member, said members being arranged for relative ironing movement when in registry, and one power means having two connections, one connection constructed and arranged for causing frame rotation, the other connection constructed and arranged for causing said relative ironing movement.

8. Apparatus of the class described, comprising a head member, a rotatable frame provided with a plurality of bed members adapted to be carried by frame rotation into and out of registry with said head member, means controlled by frame rotation for producing relative ironing movement between said head member and a bed member in registry therewith, and means controlled by said relative ironing movement of said head and bed members for causing rotation of said frame.

9. Apparatus of the class described, comprising a head, a bed movable laterally into and out of registry with said head and movable substantially vertically into and out of ironing engagement with said head, a spring adapted when in stressed condition to move said bed out of registry, a vertically positioned piston and cylinder construction beneath said head adapted to move a bed in registry into ironing engagement with the head, a connection between said piston and spring adapted to place said spring in stressed condition by movement of said piston in ironing-engagement-producing direction, means for holding said spring in stressed condition, and means for releasing said holding means when said bed moves out of ironing engagement.

10. Apparatus of the class described, comprising a head, a bed movable laterally into and out of registry with said head and movable substantially vertically into and out of ironing engagement therewith, a spring adapted when released from stressed condition to move said bed out of registry, a vertically acting piston motor beneath said head adapted to move said bed in registering position into ironing engagement with said head, a connection between said piston and spring adapted to place said spring in stressed condition by upward movement of said piston, means for thereafter holding said spring in stressed condition and means for releasing said spring from stressed condition upon downward movement of said piston.

11. Apparatus of the class described, comprising a head, a bed movable laterally into and out of registry with said head and movable substantially vertically into and out of ironing engagement therewith, a spring adapted when released from stressed condition to move said bed out of registry, a piston motor having an operative connection with said bed in registering position to move said bed into ironing engagement with the head, and said piston and spring being so constructed and arranged that a stroke of the piston in one direction places and locks said spring in stressed condition and a stroke of the piston in the other direction releases said stressed spring.

12. Apparatus of the class described, comprising coacting head and bed members having relative movement into and out of registry and rela-

5 relative movement into and out of ironing engagement, power means for causing one of said movements, means for storing part of the power exerted by said power means, and means for utilizing said stored power to cause another of said movements.

10 13. Apparatus of the class described, comprising a head, a plurality of beds movable selectively into and out of registry with said head and movable when in registry into and out of ironing engagement therewith, power means for moving a registered bed into ironing engagement with the head, means for storing part of the power exerted by said power means, and means for utilizing said stored power to move a second bed into registry with the head.

15 14. Apparatus of the class described, comprising coacting head and bed members having rela-

tive movement into and out of registry and relative ironing movement when in registry, power means controlled by relative movement of said members into registry for automatically causing said relative ironing movement, and means energized by said relative ironing movement for automatically causing movement out of registry.

15 15. Apparatus of the class described, comprising coacting pressing members relatively movable in a substantially horizontal direction into and out of registry and relatively movable in a substantially vertical direction when in registry, power means for causing said relative movement in one direction, means for storing part of the power exerted by said power means, and means for utilizing said stored power to cause said relative movement in the other direction.
